UNITED STATES PATENT OFFICE.

CYRUS YEISER, OF NEWMANSTOWN, PENNSYLVANIA, ASSIGNOR OF ONE-HALF TO M. A. YINGST, OF SAME PLACE.

PLOWSHARE.

SPECIFICATION forming part of Letters Patent No. 257,807, dated May 9, 1882.

Application filed December 13, 1881. (Model.)

To all whom it may concern:

Be it known that I, CYRUS YEISER, of Newmanstown, in the State of Pennsylvania, have invented certain new and useful Improvements 5 in Plows; and I do hereby declare that the following is a full, clear, and exact description thereof, reference being had to the accompanying drawings, and to the letters of reference marked thereon, which form part of this specification.

This invention relates to plows; and the nature of my invention consists in a novel mode of constructing the share and the landside-bar, whereby the share and bar are made 15 of separate pieces secured together, as will be hereinafter explained.

In the annexed drawings, Figure 1 is an elevation of the mold-board side of the plow, showing part of a mold-board, the plow-beam, 20 and landside-plate applied to the detachable landside-bar and share. Fig. 2 is a perspective view of the landside-bar and its share together. Figs. 3 and 4 are perspective views of the landside-bar and share detached.

25 The following description of my invention, when taken in connection with the annexed drawings, will enable others skilled in the art to understand it.

A designates the landside-bar, which terminates at one end in a plow-point, B, and which is formed with a recess, C, a horizontal offset, D, and a vertical perforated ear, E, arranged on one side of the bar. The recess C is a narrow oblong depression extending forward and downward, so that it is diagonal with respect to the length of the bar A. The base of this recess extends deeper into the side of the bar than the upper extremity, as indicated by dotted lines, Fig. 3. This inclined 35 recess C is at the junction of the point B with the parallel sides of the bar, and in rear of the recess the offset D is formed on the mold-board side of the bar. It is a horizontal table located a short distance below the top edge 40 of the bar A, and it has two holes, a a', vertically through it, one in rear of the other. In rear of the offset D is the perforated ear E, which rises a short distance above the top edge 45 of the bar, as clearly shown in Fig. 2.

The share G is formed with a horizontal table or bed, b, which is provided with vertical holes, which, when the share and table are adjusted in place against the side of the bar A, will exactly register with the holes a a' through the offset D. The point of the share G has a 50 tenon, c, formed on it, which, in size, shape, and inclination, corresponds to the recess C in the bar A. When the share is adjusted in its place to the bar the tenon c is received tightly in the recess C, and the table b of the share is 55 solidly supported on the offset D, its upper surface being flush with the top of the landside-bar. The share is then rigidly secured to the bar A by means of a bolt and nuts d, and a bolt and nuts, e, which latter bolt passes up 60 through the mold-board I and is rigidly secured to the beam H. The standard or landside-plate is secured to the ear E and to the beam by means of bolts. It will be seen that 65 the share is rigidly secured to the bar A, and that it can be easily detached from it for sharpening, or for substituting a new share in its place.

It is obvious that the bars may be adapted for right or left hand shares.

Having thus fully described my invention, what I claim as new, and desire to secure by Letters Patent, is—

1. The landside-bar A, having the point B, the inclined recess C, the perforated offset D, 80 and the perforated ear, formed as described, and for the purpose set forth.

2. The share G, having a perforated table, b, and a tenon, c, formed as described, and for the purposes set forth.

3. The combination of the bar A, its point B, inclined recess C, and perforated offset D, with the share G, its perforated table b, tenon c, and bolt-fastenings, substantially as described.

In testimony that I claim the foregoing as my own invention I affix my signature in presence of two witnesses hereto.

CYRUS YEISER.
